UNITED STATES PATENT OFFICE

JOHN F. O'CONNOR, OF CHICAGO, ILLINOIS, ASSIGNOR TO W. H. MINER, INC., OF
CHICAGO, ILLINOIS, A CORPORATION OF DELAWARE

CAR CONSTRUCTION

Application filed April 9, 1928. Serial No. 268,560.

This invention relates to improvements in car construction, and particularly to means for locking the body bolsters to the truck members of railway cars.

One object of the invention is to provide means for locking the body bolster to the transom or arch member of the truck of a railway car, including a king pin and detachable holding device which interlock with the pin and the arch or transom member to act as a safety device and prevent removal of the pin and separation of the body bolster from the truck.

Another object of the invention is to provide a rugged connection between the arch or transom member of a railway car truck and the truck bolsters, wherein the connecting means comprises relatively heavy trunnion members fixed to the truck bolsters and co-operating bearing members on the arms of the arch or transom members, and wherein the parts are secured together by bolts or pins extending through the trunnion members and portions of the arms of the transom or arch member.

More specifically, an object of the invention is to provide means for locking the body bolster to the arch or transom member of the truck of a railway car, which is efficient and reliable and prevents accidental separation of the parts, including a king pin extending through the body bolster and into a recess provided in the transom member, the pin being locked to the transom member by a sectional locking member detachably mounted on the transom member and held against movement in a vertical direction with respect to said member and embracing the corresponding end of the pin and co-operating with an annular shoulder thereon, thereby holding the pin against endwise movement in a vertical direction, the opposite end of the pin being headed, and engaging abutment means on the body bolster to prevent separation of the bolster and the truck member.

Other and further objects of the invention will more clearly appear from the description and claims hereinafter following.

In the drawing, forming a part of this specification, Figure 1 is a top plan view of a body bolster and co-operating arch member and truck bolsters of a railway car, illustrating my improvements in connection therewith. Figure 2 is a vertical, longitudinal, sectional view, corresponding substantially to the line 2-2 of Figure 1. Figure 3 is a horizontal, sectional view, corresponding substantially to the line 3-3 of Figure 2.

In said drawing, 10-10 indicate the two transversely disposed truck bolster members of a railway car truck. The body bolster of the car is designated by 11, and 12 indicates the arch or transom member of the truck. The transom member 12 is of spider form and has four substantially radially projecting arms 13-13, two of which are disposed in front of the body bolster and the remaining two in back of the same. The extremities of the arms 13 are supported on the body bolsters 10, each bolster 10 being provided with up-standing brackets 14, each of which have spaced trunnion members 15 formed integral therewith. The extremity of each arm 13 is provided with a bearing member 16 which has a semi-cylindrical bearing section co-operating with the trunnion members 15-15. The bearing member of each arm 13 is provided with vertical walls 17-17, at the opposite ends and central partition webs 18 which are disposed between the two spaced trunnion members of each supporting bracket 14. The extremities of the arms 13 are secured to the trunnion portions of the supports 14 by retaining pins 19 which extend through aligned openings in the trunnion sections 15, 85 the end walls 17 and the partition webs 18 of the corresponding arms. Endwise removal of the pins 19 is prevented by cotter retaining pins in the usual manner.

It will be evident that the connections be-

tween the extremities of the arms 13 and the trunnions of the supporting members 14 of the truck bolsters provide an exceptionally rugged supporting means, inasmuch as the trunnions present relatively large bearing areas with which the bearing members on the ends of the arms 13 co-operate. The weight of the body bolster and the car which is carried thereby is thus supported substantially entirely by the trunnion members and the pins 19 are not subjected to distortion or shearing action.

The arch member 12 is provided with a top bearing section 20 at the center thereof, which, as shown, presents a hollow spherical top bearing surface or seat 21 with which the center bearing member of the body bolster co-operates. At the center, the bearing member 20 is provided with a frusto-conical portion 22 for a purpose hereinafter described. The central portion of the arch or transom member has top and bottom wall sections 23 and 24 united at the center by a relatively heavy section 25. As shown, the top wall section 23 forms an integral part of the bearing member 20. The central section 25 is provided with a vertically disposed center pin-receiving opening 26 which is closed at the bottom by a wall 27. The wall 27 is provided with a perforation 28, through which a suitable tool may be inserted to drive out the center pin. The opening 26 is of substantially uniform diameter throughout and is intersected by a traverse opening 29 which is of substantially rectangular cross section presenting flat side walls and flat top and bottom walls. The opening 29 is adapted to accommodate a sectional locking device, hereinafter more fully described.

The body bolster 11 of the car is provided with a bearing section 120 on the lower side thereof, which is of spherical form and co-operates with the bearing section 20 of the transom member. The central portion of the bearing section 120 is recessed, as indicated at 122, to correspond with the projection 22 on the bearing member of the transom, and receives the same. As will be evident, the co-operating bearing members 20 and 120 form the center bearing member proper, and the interengaging parts 22 and 121 prevent lateral displacement of the bearing members with respect to each other. The central portion of the body bolster 11 is provided with a vertical center or king pin receiving opening 30, which is centrally enlarged in diameter, as indicated at 31, and is provided with an enlarged section 32 at the upper end, adapted to accommodate the head of the king or center pin. The improved connecting means proper for the body bolster and the arch or transom member of the truck of a railway car comprises, broadly, a king or center pin A of special design, and

a co-operating sectional locking member B.

The pin A has a substantially cylindrical main body portion which fits the opening 30 of the body bolster. The pin is headed at its upper end, as indicated by 33, the head 33 being seated in the enlarged portion 32 of the opening in the body bolster. The lower end portion of the pin, which extends into the opening 26 of the transom member, is cut away circumferentially as indicated at 34, thereby providing a reduced section and a headed lower end portion, indicated by 35. The head portion 35 is of the same diameter as the main body portion of the pin and may be freely inserted through the opening 30 of the body bolster and the opening 26 of the transom member.

As clearly shown in Figure 2, the cut away portion of the pin A registers with the opening 29 of the transom member and is of slightly greater extent in height than said opening. The head portion 35 of the pin is of such a height or thickness that it substantially fits the portion of the opening 26 below the transverse opening 29 of the transom member and has the upper face thereof flush with the bottom wall of said opening 29.

The sectional connecting member B of my improved device comprises two relatively heavy blocks which fit the opening 29 of the transom member. Each block is provided with a semi-cylindrical opening 36 on the inner side thereof, adapted to fit the corresponding side of the reduced cylindrical portion 34 of the king pin member A. The two blocks, when assembled and placed in position within the opening 29, substantially embrace the reduced section of the king pin and prevent vertical displacement of the same by engagement with the head section 35 thereof. As will be evident, movement in a downward direction of the pin A is prevented by engagement of the head with the bottom wall of the opening 26. The pin is thus held against vertical displacement both upwardly and downwardly by the retaining blocks. To hold the blocks permanently assembled with the arch member and secured to the pin, I provide retaining means comprising two bolts 37 extending through aligned openings in the blocks at opposite sides of the openings 36.

To unite the arch member of the truck of the car and the body bolster, the pin A is inserted from the top of the body bolster through the opening 30 and the lower end portion thereof inserted into the opening 26 of the arch or transom member 12. With the pin in this position and the head 35 at the lower end thereof resting on the bottom wall 27 of the opening of the arch member, the blocks of the sectional connecting member B are inserted from opposite sides into the opening 29 of the arch member and en-

gaged with the reduced section of the pin A. When thus engaged, the parts of the sectional member B are secured together by the bolts 37. When thus secured together, accidental removal of the parts of the sectional locking member B is not possible. The sectional member B snugly fits the opening 29, thereby preventing vertical displacement of the same, and due to engagement of the head 35 of the pin by the bottom sides of the blocks of the sectional member upward movement of the pin is positively prevented. It will thus be evident that the head 35 of the pin is effectively locked against upward and downward movement with respect to the transom member by the bottom wall 27 of the opening 26 and the sectional locking member B. The head 32 at the upper end of the pin which co-operates with the annular shoulder at the bottom of the enlarged section 32 of the recess 30 prevents lifting of the body bolster off of the transom.

From the preceding description, taken in connection with the drawing, it will be evident that I have provided an exceedingly simple and reliable locking means which prevents separation of the body bolsters of a car and the trucks of the same; in addition, the means provided is readily detachable, thereby facilitating disassembling of the parts and removal of the truck with respect to the car for the purpose of repairs or replacements.

A decided advantage is obtained by providing means which is readily removable or detachable for locking the king or center pin of the car to the body bolster and transom member of the truck, in that accidental separation of the parts and lifting the body bolster off of the truck is entirely prevented, thus reducing the danger of accidents due to the separation of the bolsters and the trucks.

While I have herein shown and described what I consider the preferred manner of carrying out my invention, the same is merely illustrative, and I contemplate all changes and modifications which come within the scope of the claims appended hereto.

I claim:

1. In a center connection for railway cars having a body bolster and co-operating truck transom member, the combination with a center pin connecting said members, said pin being headed at one end, said head co-operating with abutment means on one of said members, said pin extending into the other member, the portion of the pin extending into said member being notched; of a removable sectional locking member, each section of said member engaging with the notched portion of the pin; and means for securing the sections of the locking member to each other and maintaining the same in locking engagement with the pin, said lock-

ing member being held against vertical movement with respect to the member by which it is carried and holding said pin against vertical displacement by engagement with the notched section thereof.

2. In a connection for body bolster members and truck members of railway cars, the combination with a pin for connecting said members, said pin extending through aligned openings in the same and being headed at both ends, the head at one end being of a size to freely pass through said openings; of detachable, separable locking means embracing the shank of the pin adjacent the last-named head, to prevent vertical movement of the pin, said detachable means being held against vertical displacement with respect to the member in which it is mounted, by abutment means co-operating with top and bottom sides of said separable means.

3. In a swiveled connection for the body bolster member and the transom member of a truck of a railway car, the combination with a headed pin extended through one of said members and extending into the other member, the portion of the pin extending into the last-named member being provided with an annular groove; of sectional locking means engaging said groove and embracing the pin to lock the pin to said last-named member, said sectional locking means being removably mounted with respect to the pin and means on said last-named member for holding the sectional means against vertical displacement.

4. In a swiveled center connection for a body bolster member and a transom member of a railway car, wherein said members are provided with aligned center pin receiving openings, the combination with a center pin extending through the opening of one of said members into the opening of the other member, the end of said pin extending into the last-named member being provided with an annular shoulder; of a sectional locking block removably mounted on said last-named member and held against vertical displacement relative thereto, said sectional locking block engaging the shoulder portion of the pin and interlocking with said pin; and means for detachably securing the sections of said block together.

5. In a railway car construction, the combination with a body bolster member and a transom member of a truck bolster, said body bolster and transom being provided with aligned pin receiving openings, the pin receiving opening of the transom being provided with a bottom wall; of a connecting center pin extending through the opening of the body bolster and into the opening of the transom and having the lower end abutting the bottom wall of said last-named opening, the lower section of the pin being provided with an annular grooved portion, thereby provid-

ing a headed lower end section; removable locking blocks held against vertical displacement with respect to the transom, said locking blocks embracing the pin and engaging within said groove, thereby holding the head of the pin against upward movement with respect to the transom; and means for detachably securing said locking blocks together.

6. In a railway car construction, the combination with a body bolster member and a transom member of a railway car truck, said body bolster member and transom member being provided with aligned center pin receiving openings, the pin receiving opening of the transom member having a bottom wall, said transom member being provided with a transverse opening intersecting the pin receiving opening; of a connecting center pin extending through the opening of the body bolster member and into the opening of the transom member, and having the lower end thereof abutting the bottom wall of the pin receiving opening of the transom member, the section of the pin disposed within the transom member being reduced in diameter to provide a head at the lower end thereof; removable locking blocks laterally insertible into said transverse opening and held against vertical displacement by engagement with the top and bottom walls of said opening, said locking blocks embracing the pin and engaging the head at the lower end thereof to prevent upward movement of the pin with respect to the transom member; and means for detachably securing said locking blocks together.

7. In a railway car construction, the combination with a body bolster member and a car truck member, said members being provided with aligned pin receiving openings, one of said members being provided with a transverse seat intersecting the pin receiving opening thereof; of a connecting center pin accommodated within said openings and having a grooved portion adapted to align with the transverse seat; a sectional locking member disposed within said seat and interengaging with the groove of the pin to prevent vertical displacement of the latter, said locking member being held against vertical displacement with respect to the member carrying the same by the walls of said seat.

8. In a railway car construction, the combination with a body bolster; of a truck member swiveled thereto by means of a center bearing connection, said truck member including spaced truck bolsters and a connecting transom member which supports the body bolster, said transom member being provided with supporting arms having bearing seats at the ends thereof, and said body bolsters being provided with upstanding supporting elements having trunnion sections engaging the bearing members of the arms in supporting relation.

65 9. In a truck for railway cars, the combi-

nation with spaced truck bolsters; of a transom member, said truck bolsters being provided with bearing trunnions and said transom member being provided with co-operating bearing sections supported on trunnion members, and retaining pins for securing the transom member to the trunnions of the truck bolsters.

In witness that I claim the foregoing I have hereunto subscribed my name this 6th day of April 1928.

JOHN F. O'CONNOR.
